(57) **CLAIM**

The ornamental design for a washer foot, as shown and described.

DESCRIPTION

FIG. 1 is a top front perspective view of a washer foot; FIG. 2 is a bottom front perspective view thereof; FIG. 3 is a front elevation view thereof, the rear elevation, left elevation and right elevation views being mirror images thereof;

FIG. 4 is a top plan view thereof; and,

FIG. 5 is a bottom plan view thereof.

The broken lines shown in the drawings depict portions of the washer foot that form no part of the claimed design.
